RUBBER SPONGE BODY RUBBING DEVICE

Filed Aug. 22, 1927

INVENTOR,
C. E. McKeag;
BY
F. E. Maynard, ATTORNEY

UNITED STATES PATENT OFFICE.

CHARLES E. MCKEAG, OF LOS ANGELES, CALIFORNIA.

RUBBER-SPONGE BODY-RUBBING DEVICE.

Application filed August 22, 1927. Serial No. 214,664.

The present invention relates to bath equipment and especially to a sponge rubber strap device.

An important object is to provide a perfectly sanitary bath strap whose elements are all of water-proof material and which is devoid of fabric, and fibrous and metallic parts and has no bristles to deteriorate under soap and water effects.

Another object is to provide a body rubbing device including rubber sponges set in spaced relation on the strap so that the strap will be held away from the sides of the body at the ribs and other portions while the sponges are worked back and forth and thereby not only eliminate friction of the flat strap directly on the skin but also render it easier to vibrate the sponges to and fro over the thigh, rib and leg curves.

A further object is to provide a bath strap having a fixed rubber sponge so shaped and arranged that the strap passes axially through the sponge and this is, therefore, usable reversably and does not have to be applied with one side in a given position.

Further, an object is to provide a novel method for the manufacture of the instrument.

Still another object is to provide a sanitary, water-proof bath strap of simple, practical structure especially designed for long service by reason of its capacity to resist deterioration by action of water and bath soaps.

Other objects, advantages and features of the construction, combination and detail elements will be made manifest in the following specification of the herewith illustrated embodiment; it being understood that modifications, variations and adaptations are within the principle of the invention as claimed later.

Figure 1 is a perspective of the bath strap. Figure 2 is a cross-section through the strap and a sponge thereon. Figure 3 is a longitudinal section of a mounted sponge rubber. Figure 4 shows a form of finger-loop strap end. Figure 5 shows a step in the method of manufacture.

The preferred embodiment of the invention includes a stout, flat, flexible, rubber-composition strap 2 of desired length in two or three different sizes for use by adults and children. The ends of the strap may be provided with any desired finger or hand loops

3, as in Fig. 4, or rings 4, as in Fig. 1. In the latter case small bights 5 are made in the strap ends and the laps 6 are stitched down by cat-gut stitches 7. The rings 4 may be of celluloid, rubber or other water-proof material.

Before the finger grips are made up on the ends of the strap one or more elongated, commercial sponge rubber blocks 10 is mounted on the intermediate portion of the strap. The preferred method of mounting and fastening a block is to perforate this axially at 11 by a thin, hot blade 12, having parallel edges, while the block is suitably held, as in a knife guide G. The heat of the blade melts the engaged cell walls of the rubber and the block 10 is immediately slipped into place on the strap while the rubber in the apertured zone is adhesively tacky so that it will adhere to the rubber strap surface. The strap being of greater cross-area or section than the perforating knife the result is that the aperture walls contract upon the interposed strap and the sticky hole stock freezes or vulcanizes firmly onto the strap surface.

It is desirable to effectually close the ends of the strap receiving aperture 11 in the block 10 and this is done by means of closure bands 13 of rubber, or other water-proof material, which are crowded up against the ends of the blocks. The bands 13 contact snugly on the strap and are vulcanized or otherwise fixed in place.

In order to hold the strap away from the skin of the body at the smaller various curves thereof a plurality of the blocks is employed and these are spaced endwise from one another. Hence when the strap is pulled around the lesser curves only the rubber sponges ride on and rub the skin.

From the above it will be seen that I provide a simple, durable, water-proof and thoroughly sanitary rubber sponge bath strap of novel manufacture and combination and construction.

The sponge rubber block is adapted for acting as a porous container for various oils, liniments, or other medicaments which can, by means of the strap, be well rubbed into the skin by the user without the assistance of other individuals.

What is claimed is:

1. A sanitary bath device including a strap, a sponge rubber block having an axial aperture normally of less cross-section than that

of the strap; said block being pierced by the strap and the walls of the apertures being contractive on the strap.

2. A sanitary bath device consisting of a water-proof, rubber-composition strap having finger grip loops at its ends, and body rubbing means comprising a pair of blocks of sponge rubber penetrated axially by and fixed on the strap in spaced relation to each other, and rubber closure bands abutted

against the ends of the blocks to protect the same and cover the axial apertures entered by the strap and prevent entry of foreign matter; whereby the device is kept in a clean, sanitary condition; said strap providing for 15 the ready operation of the rubber blocks across the back of the body and limbs of and by the bather.

CHARLES E. McKEAG.
